HOLDING MEANS FOR BRUSHES

Application filed May 23, 1929. Serial No. 365,497.

My invention relates particularly to a holder for supporting and holding in place a brush blank while being operated upon for drilling and filling with bristles, in all types 5 of brushes.

The object of my invention is to provide a brush holder as above referred to, which will effectively hold a brush blank of any desired character firmly in place and with 10 the desired exactness of location, and which will withstand the repeated usage of the holder with succeeding brush blanks without shifting the brush blank from its correct position while being operated upon, as, for example, 15 for drilling or filling with bristles. The holders made in accordance with my invention are adapted for use on brushes designed for different purposes and which are, accordingly, of different shapes and sizes. Furthermore, they are so constructed that 20 while they are adapted to hold the brush blank accurately in place, nevertheless a brush blank may be readily inserted and removed without undue friction, but when in place 25 therein the brush blank will be held firmly against any accidental withdrawal of the same. Furthermore, the holder is so constructed as to accurately fit the faces of the brush blanks which are made with regularity 30 and uniformity, but need not closely fit the edges of the brush blanks which are at times variable in dimensions due to the finishing of the brush. Furthermore, a means is provided in connection with the holder for holding 35 the same accurately in position in its carrier so that the latter need not be made with very great accuracy.

While my invention may be embodied in many different forms, for the purpose of 40 illustration I have shown only certain forms of the same in the accompanying drawing, in which—

Fig. 1 is a vertical section of a brush holder made in accordance with my invention, 45 showing the same as located in a carrier provided for supporting it;

Fig. 2 is a vertical section on line 2—2 of Fig. 1;

Fig. 3 is a similar section taken on line 3—3 50 of Fig. 1;

Fig. 4 is a horizontal section taken on line 4—4 of Fig. 2; and

Fig. 5 is a vertical section of a modified form of holder adapted for receiving a curved brush blank.

In the form of my invention shown in Figs. 1 to 4, it will be understood that the brush blank is shown as applied to a drilling and filling machine as shown in my application upon brush holders for brush making machines, Serial No. 338,978, filed February 11, 1929, and my application upon drilling and inserting mechanism for brush machines, Serial No. 365,495, filed May 23, 1929. In the form of my invention shown in these figures, I have shown, particularly in Figs. 1 and 3, a movable carrier 1 which corresponds to the movable carriage 9 shown in my application Serial No. 338,978 above referred to. This carrier is provided with a pivotal support 2 which corresponds to the support 13 in said application, a pivotal support 3 being provided at the upper end which corresponds to the support 12 in the said application. This carrier has a tapered opening 4 having near the smaller end thereof a stop-pin 5 against which a brush holder 6, made preferably in the form of a die-casting, is designed to rest for positioning the same longitudinally of the carrier, although accurate positioning of the same against said pin 5 is not necessary owing to the locating of the holder by the countersinks hereinafter referred to. The holder 6 is accurately positioned by means of two hardened steel gibs 7 and 8 which are wedge shaped and which are designed for longitudinal adjustment by means of screws 9 screw-threaded therein and passing through slots 10 in the carrier 1 and having heads 11 which are supported on elongated recesses 12 which are supported in the sides of the carrier. By the adjustment of the gibs and the insertion of the holder 6 by pushing the same forwardly against the pin 5, the holder becomes fixedly and accurately held in place in the carrier 1.

The portion of the holder 6 which is thus held in the carrier is a rear extension 13 on the bottom of the holder having a recess 14 therein filled in with a plate 15 of hard rubber, bakelite, pyralin, die-casting or hard-

ened steel, or other similar material, provided with a series of countersinks 16 therein corresponding to the countersinks 16 in my previous application above referred to. In the forward portion of the holder 6 there is provided an U-shaped wall 17 in which there is positioned a lining 18 made of high grade rubber, vulcanized to a hardness similar to that used in motor mountings. This rubber lining 18 is held in place by reason of openings 20, not shown, which appear in the U-shaped wall 17 and into which the rubber is inserted during the molding of the same when applying it to the holder. The rubber used for this purpose will be solid and not spongy, but will have a slight give, and may be said to be comparable to the type of rubber used in automobile tire shoes. It will be noted, further, that the side walls of the body of rubber are thicker than the bottom wall, not shown, thereof so as to provide slightly more give to the sides than the bottom of the rubber lining, or, in other words, to provide a very solid support for the brush blank when being operated upon. In this way the drilling or filling is prevented from throwing the brush blank out of position but yet will not mar the brush blank, so that subsequent cleaning and wiping of the finished brushes are unnecessary. A lip 21 is provided all around the upper edge of the rubber lining down to a point near the lower open end of the same where the rubber lining is provided with a narrow opening 22 formed by two projections 23 in the rubber. The rubber lining at this end of the holder is held in place by means of two flat springs 24 which are secured by rivets or screws 25 to the holder. As shown in Fig. 4, the rubber lining fits the side and bottom faces of a brush blank 25a but does not fit the lower edges of the brush blank inasmuch as these edges vary in position due to the finishing operations of the brush blanks.

45 The form of my invention shown in Fig. 5 is constructed in the same way as above described, except that in this instance a holder 26 is provided, having a curved recess 27 for receiving the brush blank and a curved plate 28 having appropriately located countersinks 29 therein, the inner ends of the recesses forming the countersinks being on the same radius as the face of the brush blank.

55 In the operation of my brush holder, it will be understood that the brush blank 25a will be pushed into the holder 6 between the projections 23 and beneath the lip 21, and the gibs 7 and 8 will be set up in such a manner as to tightly fit the sides of the holder 6 when placed in the carrier and resting against the face of the stop-pin 5. Owing to the fact that the sides of the carrier which support the gibs 7 and 8 are thin there will be a certain amount of give in these sides of the carrier so that 60 the brush holder 6 will thus be tightly

clamped in place ready for the operations of drilling and filling, etc., when the holder is inserted between the gibs. The adjustment of the gibs by means of the screws 9 will furthermore allow for differences in the give and strength of the two sides of the carrier and the gibs can be set up so as to account for wear and repairs to be made in the sides of the carriers. Also, they permit recentering due to defects in the brush blanks, as, for example, very defective die pressing. In this way the carrier itself does not have to be made with great accuracy. Again, by constructing the holder in the above manner with inserts in the base of the same for countersinks, the construction is quite inexpensive. 70 75 80

Therefore, the brush blanks may be, thus, readily and quickly inserted through the entry openings into the holder 6, especially in the type of the brush blank as shown in the drawings, as the opening 22 is as wide as the innermost width between the walls of the rubber lining, and the brush blank will then be strongly and effectively held in place ready for the drilling and filling operations, etc. 85 90 95

While I have described my invention above in detail I wish it to be understood that many changes may be made therein without departing from the spirit of the same.

I claim:

1. A brush holding means comprising a carrier having an opening, a removable brush holder carried in said opening, said holder having a socket for receiving the brush blank and adapted to surround the bristle receiving portion of the brush blank. 100

2. A brush holding means comprising a removable brush holder having a socket for receiving the brush blank, said socket having a lining of yielding material. 105

3. A brush holding means comprising a removable brush holder having a socket for receiving the brush blank, said socket having a lining of solid rubber. 110

4. A brush holding means comprising a removable brush holder having a socket for receiving the brush blank, said socket having a lining of yielding material, provided with a brush blank retaining lip. 115

5. A brush holding means comprising a removable brush holder having a socket for receiving the brush blank, said socket having a lining of yielding material provided with a brush blank retaining lip and a contracted entry opening to hold the brush blank tightly in place. 120

6. A brush holding means comprising a removable brush holder having a socket for receiving the brush blank, said socket having a lining of yielding material provided with a brush blank retaining lip and a contracted entry opening to hold the brush blank tightly in place, the holder being provided also with lateral supporting springs at the entry opening. 125 130

7. A brush holding means comprising a removable brush holder open at the back and having a socket for receiving the brush blank, said holder being provided in its back in a recess open only towards the rear with an inserted interchangeable plate containing countersinks.

8. In combination, a brush holding means comprising a removable brush holder having a socket for receiving the brush blank and a carrier having a tapered opening for receiving the holder and wedging it in place.

9. In combination, a brush holding means comprising a removable brush holder having a socket for receiving the brush blank and a carrier having a tapered opening for receiving the holder and wedging it in place and a movable tapered gib in said opening for adjusting the size of the same and for accomplishing said wedging.

10. In combination, a brush holding means comprising a removable brush holder having a socket for receiving the brush blank and a carrier having thin yielding walls providing a tapered opening for receiving the holder.

11. In combination, a brush holding means comprising a removable brush holder having a socket for receiving the brush blank and a carrier having thin walls providing a tapered opening for receiving the holder and wedging it in place and a movable tapered gib in said opening for adjusting the size of the same and for accomplishing said wedging.

35 In testimony that I claim the foregoing, I have hereunto set my hand this 20th day of May, 1929.

LEONARD B. TERHUNE.
